FIG. 3.

UNITED STATES PATENT OFFICE.

CARL A. OLSON, OF MILAN, MINNESOTA.

TRACTOR.

1,166,246.

Specification of Letters Patent. Patented Dec. 28, 1915.

Application filed June 21, 1915. Serial No. 35,378.

To all whom it may concern:

Be it known that I, CARL A. OLSON, a citizen of the United States, residing at Milan, in the county of Chippewa and State of Minnesota, have invented certain new and useful Improvements in Tractors; and I do declare the following to be a full, clear, and exact description of the invention, such as will enable others skilled in the art to which it appertains to make and use the same.

My invention relates to improvements in tractors, and more particularly to mountings for the driving wheels thereof, the object of the invention being to provide extremely simple yet highly efficient construction for the attainment of the desired ends.

With this general object in view, the invention resides in certain novel features of construction and in unique combinations of parts to be hereinafter fully described and claimed.

In describing the invention, I shall refer to the accompanying drawings which constitute a part of the application and in which:

Figure 1 is a side elevation of a tractor constructed in accordance with my invention; Fig. 2 is a horizontal section, partly in elevation, taken substantially upon the planes indicated by the line 2—2 of Fig. 1; Fig. 3 is a vertical transverse section as cut on the plane indicated by the line 3—3 of Fig. 1; Fig. 4 is a central section through one of the driving wheels; Fig. 5 is a side elevation of such wheel, and Figs. 6 and 7 are details to be hereinafter referred to.

In these drawings wherein like reference characters designate corresponding parts throughout the several views, the numerals 40 1 have reference to a pair of longitudinally disposed sills which extend from one end of the machine to the other end thereof in parallel relation. The front ends of the sills 1 are supported by any preferred type of truck including wheels 2 which may be steered by actuation of the steering wheel 2^a, through the instrumentality of suitable connections forming no part of the present application. Secured to the rear ends of the sills in any appropriate manner and projecting laterally from said sills, is a transverse bar 3, while similarly secured to the intermediate portions of the aforesaid sills 1 and likewise projecting laterally in opposite directions from said sills, is an additional transverse bar 4, the outer ends

of the bars 3 and 4 being bolted or otherwise secured to a pair of supplemental longitudinally disposed sills 5 which are spaced outwardly from and lie parallel to the sills 1. 60

Bolted or secured in any other appropriate manner to the central portions of the sills 1, are the upright transversely alined posts 6 whose lower ends depend from the sills 1, while their upper ends rise considerable distances above said sills and are secured to transverse horizontally disposed bars 7 which are suitably braced at 7^a to the transverse bars 3 and 4. 65

The bars 7 project laterally beyond the upright posts 6 and are secured to additional upright posts 6^a which are alined transversely with the posts 6, but which are secured to and rise from the supplemental sills 5, the lower ends of the posts 6^a being 75 extended below said sills appropriate distances, while their upper ends continue above the bars 7 and support the rear end of an appropriate top 8, the details of which need not be entered into in the present application. 80

Disposed respectively in advance of the posts 6 and 6^a, are additional and shorter posts 9 and 9^a which rise respectively from the sills 1 and 5, while positioned in rear of said posts 6 and 6^a are other posts 10 and 10^a, all of the posts 9 and 9^a being in transverse alinement, while those indicated at 10 and 10^a are likewise alined. In the present embodiment of the invention, the upper and lower ends of the posts 9, 9^a, 10, and 10^a, are shown as held in spaced relation from their respective posts 6 and 6^a, by horizontally disposed spacing blocks 11 through which and through the posts, longitudinally disposed bolts 12 are passed. By this construction, two pairs of upright frame members are provided, such members rising from the two pairs of sills hereinbefore described, these members being of utility to become evident as the description proceeds. 95

Positioned between the sills 1 and 5 at each side of the machine, and likewise disposed between the numerous posts which are secured to said sills, are the driving wheels 105 13, the details of which are disclosed most clearly in Figs. 3, 4, and 5. Each wheel 13 comprises a ring-shaped hub member 14 having at its central portion an infernal gear ring 15, while the inner face of the hub member 14, on opposite sides of the gear ring 15, constitutes tracks upon which roll- 110

ers yet to be described are adapted to travel. Surrounding the hub member 14 and shown in the present embodiment of the invention as formed integrally therewith, is the spoke 5 receiving channel 16 in which the inner ends of a plurality of spokes 17 are anchored, the outer ends of said spokes being connected in the usual manner to a rim 18 having any preferred type of tire.

10 Disposed on opposite sides of the wheels 13 and secured in contact with the spokes 17, are the annular tracks 19 which are disposed concentric with the hub member 14 and the rim 18, said tracks serving not only to impart rigidity to the wheels, but being designed for purposes yet to be described.

Supported upon appropriate sleepers 20 which extend from the transverse bar 3 to the bar 4 and which are interposed between the sills 1, is a differential or compensating gear 21 which is here shown as driven by a chain 22 from a counter-shaft 23 driven by an engine shaft 24, the latter leading to any appropriate type of engine (not shown) 25 which is confined in a hood 25 built over the front end of the main bed frame of the machine, said differential also having connection with a transverse bar 26 which in turn is secured to the longitudinally extending rails 27, the latter being bolted or otherwise fastened to the inner sides of the posts rising from the sills 1 and being extended therefrom to points above the front and rear ends of the sills 1, upright standards 28 establishing connection between the aforesaid rails and the sills 1 at suitable intervals.

Extending from the differential 21, is the sectional shaft 29 which is positioned horizontally and rotatably mounted in bearing 40 openings formed through the alined posts 6 and 6^a, or any appropriate bearings carried by said posts. The opposite ends of the shaft 29 are provided with spur pinions 30 which engage the internal gear rings 15 of the hubs 14. Other pinions 31 (see Fig. 6) are keyed to the intermediate portions of horizontally disposed shafts 32 which are rotatably supported by the alined posts 6 and 6^a, one shaft 32 being positioned above each pinion 30, while another is disposed below said pinion as clearly shown in Figs. 1 and 3.

Mounted loosely upon the shafts 32 are the flanged rollers 33 which contact with the inner curved surfaces of the hubs 14, while additional flanged rollers 33^a are keyed to other horizontal shafts 32^a and likewise contact with the inner curved surfaces of said hubs, the shafts 32^a being supported by the 55 posts 9 and 9^a, and by those indicated at 10 and 10^a.

By arranging the numerous rollers 33 and 33^a as disclosed in the drawings, the wheels 13 are held concentric with the shaft 29, 65 but not as effectively as necessary. The an-

nular tracks 19 have therefore been provided as bracing means for the wheels, such tracks engaging grooved rollers 34 which are shown in the present embodiment of the invention as mounted upon the lower and intermediate portions of the posts 6 and 6^a, and as carried by brackets 35 projecting from the sills 1 and 5 (see more particularly Fig. 2). Although the axes of the rollers 34 could probably be positioned otherwise than as shown in the drawings, they are preferably disposed radially in respect to the tracks 19, whereby the flanges of the rollers may receive therebetween the horizontally extending flanges of said tracks, thereby reliably preventing dislocation of parts.

By constructing the tractor in the manner above defined and depicted in the accompanying illustration, it will be evident that although the machine may be manufactured at comparatively small expense, the same will be highly efficient and durable, and will possess a number of advantages, particular emphasis being laid upon the provision of the novel bracing means for the wheels (the rollers 34 and tracks 19) and upon the framework for supporting the numerous rollers at proper points for accomplishing the best results.

In the drawings, certain specific details of construction have been shown, and in the preceding such details have been described, but it is to be understood that I need not be restricted thereto otherwise than to the extent to which the appended claims limit me.

I claim as my invention:

1. In combination, a frame having supporting and steering means at its front end and including at its rear end two pairs of parallel longitudinally disposed sills, upright posts secured to and rising from the sills in transverse alinement, a driving wheel disposed between the sills of each of the aforesaid pairs, a transverse bar above the wheels to which the upper ends of the posts are secured, annular tracks carried by opposite sides of the wheels, track engaging rollers rotatably mounted on the posts, and similar rollers mounted adjacent the sills.

2. In combination, a frame having supporting and steering means at its front end and including at its rear end two pairs of parallel longitudinally disposed sills, front and rear posts rising from the sills in transverse alinement, intermediate posts rising from said sills in transverse alinement and having connections with the aforesaid posts, a driving wheel mounted between the sills of each of the aforesaid pairs, inner and outer concentric annular tracks on said wheels, rollers on the front and rear posts engaging one annular track, and additional rollers on the other posts engaging the other track.

3. In combination, a frame having supporting and steering means at its front end

and including at its rear end two pairs of parallel longitudinally disposed sills, front and rear posts rising from the sills in transverse alinement, intermediate posts likewise rising from said sills in transverse alinement, spacers between the intermediate posts and the front and rear posts, longitudinally disposed bolts passing through the posts and through said spacers, a driving wheel mounted between the sills of each of the aforesaid pairs, inner and outer concentric annular

tracks on said wheels, rollers on the front and rear posts engaging one annular track, and additional rollers on the other posts engaging the other track.

15

In testimony whereof I have hereunto set my hand in presence of two subscribing witnesses.
